(57) **CLAIM**

The ornamental design for an actuating-arm drive of a furniture flap with locking lever, as shown and described.

DESCRIPTION

1. Actuating-arm drive of a furniture flap with locking lever

1.1 : Perspective

1.2 : Front

1.3 : Back

1.4: Top

1.5 : Bottom

1.6 : Left

1.7 : Right

2.1 : Perspective

2.2 : Perspective

2.3 : Perspective

2.4 : Perspective

View 2.1. shows the locking lever in an open position and view 2.2. in a closed position.

The broken lines in the drawings depict portions of the actuating-arm drive of a furniture flap with locking lever that form no part of the claimed design. The additional broken lines in 2.3-2.4 depict environmental subject matter that forms no part of the claimed design.

1 Claim, 11 Drawing Sheets
